US0D1112449S

(12) **United States Design Patent** (10) Patent No.: **US D1,112,449 S**
(45) Date of Patent: ** Feb. 10, 2026

(54) **PROJECTOR**

(71) Applicant: **XGIMI Technology CO., LTD,**
Chengdu (CN)

(72) Inventors: **Peirong Mou**, Sichuan (CN); **Qiang Li**,
Sichuan (CN); **Shi Xiao**, Sichuan (CN);
Bo Zhong, Sichuan (CN); **Chuanqi Tang**, Sichuan (CN)

(**) Term: **15 Years**

(21) Appl. No.: **35/522,425**

(22) Filed: **Aug. 29, 2024**

(80) **Hague Agreement Data**

Int. Filing Date: **Aug. 29, 2024**

Int. Reg. No.: **DM/240203**

Int. Reg. Date: **Aug. 29, 2024**

Int. Reg. Pub. Date: **Sep. 27, 2024**

(30) **Foreign Application Priority Data**

Mar. 25, 2024 (CN) 202430154942.X

(51) **LOC (15) Cl.** **16-02**

(52) **U.S. Cl.**

USPC **D16/221**

(58) **Field of Classification Search**

USPC D16/200, 221, 230

CPC G02B 27/024; G03B 21/00

See application file for complete search history.

Assistant Examiner — Breana Copeland

(57) **CLAIM**

The ornamental design for a projector as shown and described.

DESCRIPTION

1. Projector

1.1 : Front

1.2 : Back

1.3 : Left

1.4 : Right

1.5 : Top

1.6 : Bottom

1.7 : Perspective

1.8 : Perspective

1 Claim, 8 Drawing Sheets
